DESIGN FOR AN ASH TRAY

Benjamin E. Lawrence, Chicago, Ill.

Application May 29, 1944, Serial No. 113,792

Term of patent 3½ years

(CL. D85—2)

To all whom it may concern:

Be it known that I, Benjamin E. Lawrence, a citizen of the United States, residing at Chicago, in the county of Cook and State of Illinois, have invented a new, original, and ornamental Design for an Ash Tray, of which the following is a specification, reference being had to the accompanying drawing, forming a part thereof.

In the drawing—

Fig. 1 is a perspective view looking toward the front and left side of the ash tray, showing my new design, and

Fig. 2 is a perspective view looking toward the rear and right side of the ash tray.

I claim:

The ornamental design for an ash tray, as shown.

BENJAMIN E. LAWRENCE.
